MANUFACTURE OF SHOES

Charles F. Pym, Beverly, Mass., assignor to
United Shoe Machinery Corporation, Paterson,
N. J., a corporation of New Jersey

Application February 16, 1931, Serial No. 516,024

52 Claims. (Cl. 12—14)

This invention relates to the manufacture of shoes, and in some of its aspects more particularly to the lasting of shoes in which an adhesive (hereinafter referred to as cement) is used to 5 secure a portion, at least, of the upper in lasted relation to an insole. The invention is herein illustrated by reference to the lasting of the toe ends of shoes with cement, but it is to be understood that in its more general aspects it is not 10 limited to the lasting of toes nor to the use of cement for securing the upper in lasted position.

In lasting the toe ends of shoes with cement it is customary to apply to the marginal portion of the upper some temporary upper-holding means 15 which is portable with the shoe and maintains the upper in lasted position until the cement has set, after which the upper-holding means is removed from the shoe. The present invention, in one important aspect, has in view such treatment 20 of the upper as to accelerate the setting of the cement, and thus to eliminate the necessity for such temporary upper-holding means, thereby saving time and effecting other economies in the manufacture of shoes. A further object is to 25 accomplish improved results in the lasting operation. To these and other ends, the invention provides a novel method including, as one of its steps, the application of heat to the marginal portion of the upper. In accordance with the 30 procedure herein illustrated the toe end of the upper is conformed to the contour of the last by the use of wipers which wipe it heightwise of the toe and lay its marginal portion inwardly over the insole, after which, while the upper is clamped 35 about the toe to hold it in conformity to the contour of the last, a heated presser is applied to its marginal portion. Preferably, as illustrated, the wipers are unheated, so that the upper may be shaped as required without danger of injury 40 through excessive heat to any portion thereof which is visible in the finished shoe. After a very short application of the pressure and heat to the marginal portion of the upper, it is so effectively secured in lasted position by the cement that the 45 shoe may be subjected immediately to the next manufacturing operation without the use of any extraneous upper-holding means at the toe. Economies of time, labor and materials are thus effected in the manufacture of the shoe. The 50 shrinking action of the heat, moreover, is especially useful in eliminating wrinkles in the gathered margin of the upper, so that the upper is pressed smooth and flat upon the insole. It is further contemplated that, if conditions render 55 it desirable, the heated presser will be moved in-

wardly in wiping engagement with the upper, to insure that the upper will be drawn tightly inward from the edge of the shoe bottom and also to assist in smoothing it free from wrinkles, such movement of the presser, as illustrated, being effected by action of the wipers thereon. 60

In a further aspect the invention provides a novel organization of means for operating on shoes, the construction shown being especially adapted for use in the practice of the above-described method. For the purposes in view, the illustrated machine comprises toe-embracing wipers for conforming the toe end of the upper to the contour of the last and for laying its margin inwardly over the insole, means for clamping the 65 upper about the toe to hold it in conformity to the contour of the last, and a heated presser for engaging the marginal portion of the upper and pressing it upon the insole. As illustrated, the presser comprises a member curved similarly to 70 the contour of the edge of the toe end of the shoe bottom and so mounted as to permit it to be moved lengthwise of the shoe by the action of the wipers thereon. The presser is supported on a carrier whereby it may be swung into or out of 75 position over the toe end of the shoe bottom, and the carrier is connected to a treadle for operating the presser to press it downwardly upon the upper independently of the wipers. 80

It will be understood that the above-described 85 method and means are not limited in utility to the lasting of shoes with any particular kind of cement, although it is contemplated that pyroxylin cement will give especially good results because of the rapidity with which it will set under 90 the application of heat. The invention, moreover, in some of its aspects, does not depend for utility upon the use of cement applied extraneously to the upper materials, since under some conditions box toe stiffening material will be so 95 affected by the pressure and heat, applied as hereinabove described, as to maintain the upper securely in lasted position. Furthermore, with respect to means for pressing the marginal portion of the upper upon the insole, the invention 100 in some novel aspects is not limited to a heated pressing member, since the use of a presser separate from the wipers may be of advantage regardless of the presence of heat, as hereinafter explained. 105

The method in its various novel aspects and the novel mechanical features provided by the invention will now be more particularly described by reference to the accompanying drawings and pointed out in the claims. 110

In the drawings,

Fig. 1 is a view in front elevation of the left-hand portion of a bed-lasting machine adapted for use in the practice of the method and in which 5 novel features of the invention are embodied;

Fig. 2 is a perspective view of a portion of the machine, showing the heated presser applied to the marginal portion of the toe end of the upper; and

10 Figs. 3, 4 and 5 are views partly in elevation and partly in section illustrating more fully different steps in the treatment of the shoe.

The machine herein shown is one of a well-known type, many of the characteristic features 15 of which, relating especially to the means for lasting the toe end of the shoe, are shown and described in detail in Letters Patent No. 1,284,870, granted on November 12, 1918 upon an application of Matthias Brock, and in Letters Patent No. 20 1,495,169, granted on May 27, 1924 upon an application of Joseph Fausse and René E. Duplessis. Only such portions of the general organization of the machine, therefore, as it is necessary to refer to for an understanding of this invention will be 25 herein described.

The machine is provided with a shoe support comprising a spindle 10 adapted to enter the spindle hole in the heel end of the last and a toe rest 12 for supporting the toe-end portion of the shoe and last. The shoe thus mounted is embraced by a heel band 13 which clamps and holds its heel-end portion and also maintains its toe end pressed firmly down upon the toe rest 12. For wiping the toe-end portion of the upper heightwise of the last and for laying its marginal portion inwardly over an insole on the last there are provided toe-embracing wipers 14 operated by a hand lever 16, and controlled by the same hand lever is a toe band 18 which embraces and clamps the upper about the toe to hold it in conformity to the contour of the last after the upwiping operation. The toe-lasting means, including the wipers and the toe band, is supported on a slide 20 connected by a link 22 to a treadle 24 whereby the operator is enabled to raise and lower the wipers as desired. It will be understood that in the customary use of a machine of this type the wipers are first advanced and closed about the toe by the lever 16 below the plane of the shoe bottom and are then raised by the treadle to wipe the upper heightwise of the toe to the edge of the insole, after which they are further advanced and closed by the hand lever to wipe the marginal portion of the upper inwardly over the insole. By 50 means of the treadle also the wipers may be forced downwardly to increase their pressure on the marginal portion of the upper and may be raised to prevent them from dragging on the upper when they are retracted by the hand lever. 55 When the wipers are advanced and closed inwardly over the shoe bottom after the upwiping operation, the toe band 18 is applied in clamping and holding engagement with the upper, as fully disclosed in Letters Patent No. 1,495,169. The 60 illustrated machine also includes in its organization means whereby the toe band 18 is held in clamping engagement with the upper while the wipers are retracted from over the shoe bottom, and connections permitting a limited amount of 65 upward and downward movement of the wipers without altering the relation of the toe band to the shoe, as shown and described in detail in Letters Patent No. 1,825,857, granted on October 6, 70 1931 upon an application of F. C. Eastman.

75 For purposes of this invention the machine is

provided with means for applying pressure and heat to the marginal portion of the toe end of the upper after the upper has been operated upon by the wipers 14 and while it is held in conformity to the contour of the last by the toe band 18.

This means comprises a presser member or block 26 having a contour similar to that of the edge of the toe end of the shoe bottom and with its lower intermediate portion recessed to provide a curved upper-engaging portion preferably of a width somewhat less than that of the marginal portion of the upper extending inwardly over the insole. The block 26 is supported on the end of an arm or carrier 28 which is slidably movable lengthwise in a holder 30 supported on a vertical rod 32. This supporting means and its operating mechanism, in the machine herein shown, are of substantially the same construction as means provided heretofore in machines of the illustrated type for supporting a holdown member and for pressing the member upon the shoe bottom, as disclosed in Letters Patent No. 1,120,822, granted on December 15, 1914 upon an application of E. L. Keyes. As more fully illustrated in the last-mentioned Letters Patent, the

rod 32 is connected by a link 34 to a treadle 36 which is normally held in upraised position by a spring 38 and is locked in depressed position by mechanism controlled by a releasing lever 40. The holder 30 is mounted to turn about the rod 32 and by means of a spring 33 (Fig. 1) is held normally in a position in which the block 26 is retracted from over the shoe bottom. Between the holder 30 and the rod 32 there is a spiral slot-and-pin connection 42 whereby the carrier arm 110 28 is lowered as it is swung forwardly by the operator to position the block 26 over the toe end of the shoe. A lever 44 mounted on the holder 30 and connected to the arm 28 enables the operator to slide the arm forwardly or rearwardly 115 to position the block 26 in its proper location widthwise of the shoe. It will be understood that the block is pressed downwardly upon the upper by depression of the treadle 36, whereupon the treadle is locked to maintain the pressure as long as desired. When the block is pressed down on the upper it is permitted to adjust itself to the contour of the shoe bottom by a universal connection with its supporting arm 28, comprising a ball-shaped end 46 on the arm which is seated 120 in a depression in the block and is overlapped by a lug 48 fast on the block. The block 26 is maintained in a heated condition by a pair of electrical heating units 50 which are mounted in recesses within it and are supplied with electrical current through a flexible cable 52. To assist the operator in positioning the block in proper relation to the shoe, there is provided a wooden handle 54 which is mounted on a strap 56 fast on the block.

In the use of the illustrated machine to practice the novel method in the lasting of the toe end of a shoe with cement, the toe end of the upper may be wiped upwardly to the edge of the insole by the wipers 14, its marginal portion 140 wiped inwardly over the insole by the wipers, and the upper clamped about the toe by the toe band 18, as usual in the operation of machines of the illustrated type, the positions of the parts at the end of the overwiping operation being illustrated in Fig. 3. These operations are preferably performed before cement is applied to the margin of the upper materials. Thereafter the operator retracts the wipers from over the shoe bottom, the toe band remaining in clamping position, and

- in accordance with one well-known mode of procedure he may then trim away the portions of the lining and of the box toe stiffener which project beyond the edge of the insole, thereafter applying cement to the marginal portion of the upper leather. After again using the wipers to lay the cement-coated margin of the upper over the insole or, if desired, without such use of the wipers, the operator then brings the heated presser block 26 into proper position over the toe end of the shoe and adjusts it in engagement with the inwardly extending margin of the upper, pressing it down upon the shoe bottom by means of the treadle 36. Preferably the block 26 will be positioned initially at some distance forwardly of the inner edge of the margin of the upper at the end of the toe, as illustrated in Fig. 4. While pressing the block downwardly with the treadle the operator then advances the wipers 14 from the position illustrated in Fig. 4 over the edge of the shoe bottom and against the block 26, and by further movement of the wipers forces the block rearwardly to the position illustrated in Fig. 5. This serves to insure that the upper at the end of the toe, where the wrinkles in the margin are more prominent than at the sides of the toe, will be drawn tightly inward from the edge of the shoe bottom, the movement of the heated block also having an ironing effect on the upper which assists in pressing it smooth and flat upon the insole. The operator may then further depress the treadle 36 to increase the pressure of the block on the upper. Thereafter the heated block is maintained by the treadle-locking mechanism in pressure-applying relation to the upper until the cement, under the action of the heat, has set sufficiently to maintain the upper securely in lasted position. In the use, for example, of pyroxylin cement this will require only a few seconds. Thereafter the operator, by pressing on the lever 40, releases the treadle 36, whereupon the block 26 is raised from the shoe and swung rearwardly to its idle position. The shoe may then be removed from the machine and subjected immediately to the next manufacturing operation without the use of any extraneous upper-holding means at the toe.
- While the invention has thus been described with particular reference to the use of cement for securing the upper to the insole, it should be understood that the method and means disclosed may be usefully employed in the lasting of toes in which the marginal portion of the upper includes box toe stiffening material of a kind that hardens rapidly under the influence of heat, since the hardened stiffening material will serve of itself to maintain the upper in lasted position. Furthermore, the useful effects of the heat and pressure in shrinking and flattening the marginal portion of the upper are not dependent upon the character of the means whereby the upper is secured or held in lasted relation to the insole. In lasting with cement, moreover, there is an advantage, regardless of the heating effect, in the use of the presser block 26 to press the marginal portion of the upper down upon the insole, since the block may engage the upper, as illustrated, farther inwardly from the edge of the shoe bottom than it is practicable to move the wipers because of the danger of fouling the edges of the wipers with cement and consequently damaging the outer surface of the upper in lasting the next shoe.
- Having described the invention, what I claim as new and desire to secure by Letters Patent of the United States is:
1. That improvement in methods of making shoes which consists in conforming an upper to the contour of a last and laying its marginal portion inwardly over an insole on the last without the application of heat to the upper, and thereafter, while pressing the upper against the last exteriorly of the shoe bottom but near the edge of the insole to hold it in conformity to the contour of the last, placing a previously heated pressing member upon the shoe bottom in direct contact with the inwardly extending marginal portion of the upper and through said member pressing the marginal portion of the upper upon the insole and applying heat thereto. 80
  2. That improvement in methods of making shoes which consists in conforming an upper to the contour of a last and laying its marginal portion inwardly over and pressing it upon an insole on the last without the application of heat to the upper, clamping the upper against the last near the edge of the insole exteriorly of the shoe bottom to hold it in conformity to the contour of the last, and while thus holding the upper releasing a portion at least thereof lying over the insole from the pressure applied and engaging the released portion with a previously heated presser to press that portion firmly upon the insole while applying heat thereto. 90
  3. That improvement in methods of making shoes which consists in conforming an upper to the contour of a last and laying its marginal portion inwardly over an insole on the last without the application of heat to the upper, and thereafter, while holding the unheated upper in conformity to the contour of the last by pressing it against the sides of the last, applying a heated presser to its marginal portion and moving the presser along the surface of the upper to iron it. 100
  4. That improvement in methods of making shoes which consists in laying the marginal portion of an upper inwardly over an insole by the use of a wiper, retracting the wiper and applying a heated presser to the marginal portion of the upper to press it upon the insole, and then forcing the presser inwardly in wiping engagement with the upper by use of the wiper. 110
  5. That improvement in methods of making shoes which consists in conforming an end of an upper to the contour of a last and laying its marginal portion inwardly over an insole on the last without the application of heat to the upper, and thereafter placing upon the overlaid marginal portion of the upper around the end of the shoe bottom a previously heated pressing device and moving said device lengthwise of the last in wiping contact with the upper while applying pressure and heat to the upper. 125
  6. That improvement in methods of making shoes which consists in laying the marginal portion of an end of an upper inwardly over an insole by the use of wipers, applying clamping pressure around the end of the upper exteriorly of the shoe bottom and retracting the wipers, and while holding the upper thus clamped with the wipers retracted applying a heated presser in contact with its marginal portion around the end of the shoe bottom to press it upon the insole. 135
  7. That improvement in methods of making shoes in which an end portion of the upper is secured to an insole by an adhesive between the upper and the insole, which consists in conforming the end of the upper to the contour of a last and laying its marginal portion inwardly over and pressing it upon an insole on the last without the application of heat to the upper, clamping the 140
  - 145
  - 150

- upper around the end of the last exteriorly of the shoe bottom to hold it in conformity to the contour of the last, and while thus holding the upper releasing a portion at least thereof lying over the insole from the pressure applied and engaging the released portion with a previously heated presser to press that portion firmly upon the insole while applying heat to render the adhesive quickly effective to secure it to the insole. 14. In a lasting machine, the combination with means for working an upper heightwise of the last into conformity to the contour of the last and for holding it thus conformed, of additional means for applying heat to the marginal portion of the upper and for pressing it upon an insole on the last along the same portion of the shoe as said first-named means while the upper is thus held, and a movably mounted support for said additional means arranged to carry said means into and out of operating position. 80
- 10 8. That improvement in methods of lasting shoes in which the toe end of the upper is secured to an insole by an adhesive between the upper and the insole, which consists in conforming the toe end of the upper to the contour of a last and laying its marginal portion inwardly over an insole on the last by the use of wipers, clamping the upper about the toe exteriorly of the shoe bottom and retracting the wipers, and while holding the upper thus clamped with the wipers retracted applying a heated presser to the marginal portion of the upper to press that portion upon the insole and to render the adhesive quickly effective to secure it to the insole. 15. In a lasting machine, the combination with means for conforming an upper to the contour of a last and for shaping its marginal portion over an insole on the last, of means for holding the upper in conformity to the contour of the last, and a device for applying heat to the marginal portion of the upper and for pressing it upon the insole along the same portion of the shoe as said first-named means while the upper is thus held. 90
- 15 19. That improvement in methods of lasting shoes in which the toe end of the upper is secured to an insole by an adhesive, which consists in conforming the toe end of the upper to the contour of a last and laying its marginal portion inwardly over an insole on the last by the use of unheated wipers, clamping the upper about the toe to hold it in conformity to the contour of the last and retracting the wipers, then applying an adhesive to the marginal portion of the upper, and thereafter, while holding the upper clamped about the toe, applying a previously heated presser to its marginal portion to press it upon the insole. 20. In a lasting machine, the combination with means for conforming an upper to the contour of a last and for laying its marginal portion inwardly over the bottom of the last, of means for pressing on the upper near the edge of the last bottom to hold it in conformity to the contour of the last, and a device for applying pressure and heat to the previously overlaid marginal portion of the upper while the upper is held by said pressing means. 95
- 20 16. In a lasting machine, the combination with a work support, and means for wiping an upper into conformity to the contour of a last on said support, of additional means for applying heat to the marginal portion of the upper and for pressing it upon an insole on the last along the same portion of the shoe as said wiping means while the last is on said support, and a movably mounted support for said additional means arranged to carry said means into and out of operating position. 100
- 25 17. In a lasting machine, the combination with means for conforming an upper to the contour of a last and for laying its marginal portion inwardly over the bottom of the last, of means for pressing on the upper near the edge of the last bottom to hold it in conformity to the contour of the last, and a device for applying pressure and heat to the previously overlaid marginal portion of the upper while the upper is held by said pressing means. 110
- 30 18. In a machine for lasting shoes in which the upper is secured to an insole by an adhesive, the combination with means for conforming an upper in an unheated condition to the contour of a last by working it heightwise of the last and for holding it thus conformed, of a device for pressing the marginal portion of the upper upon an insole on the last while the upper is thus held and for also heating said marginal portion to render the adhesive quickly effective to secure it to the insole, a support for said device movable to carry the device toward operating position, and means for guiding said support in its movement. 115
- 35 19. In a machine for lasting shoes in which the upper is secured to an insole by an adhesive, the combination with unheated means for conforming an upper to the contour of a last and for shaping its marginal portion over an insole on the last, of means for holding the upper in conformity to the contour of the last, and a heated device for pressing the marginal portion of the upper upon the insole while the upper is thus held and for also applying heat to said marginal portion to render the adhesive quickly effective to secure it to the insole. 120
- 40 20. In a machine for lasting shoes in which the upper is secured to an insole by an adhesive, the combination with a work support, and means for conforming an upper to the contour of a last and for laying its marginal portion inwardly over an insole on the last, of means for holding the upper in conformity to the contour of the last, and a device for pressing the marginal portion of the upper upon the insole while the last is on said support and for also applying heat to said mar- 125
- 45 13. That improvement in methods of making shoes in which the marginal portion of the toe end of the upper is secured to an insole by an adhesive, which consists in laying the marginal portion of the toe end of the upper inwardly over an insole by the use of wipers, retracting the wipers and applying a heated presser to the marginal portion of the upper to press it upon the insole, and then forcing the presser inwardly in wiping engagement with the upper by use of the wipers. 130
- 50 14. In a machine for lasting shoes in which the upper is secured to an insole by an adhesive, the combination with unheated means for conforming an upper to the contour of a last and for shaping its marginal portion over an insole on the last, of means for holding the upper in conformity to the contour of the last, and a heated device for pressing the marginal portion of the upper upon the insole while the upper is thus held and for also applying heat to said marginal portion to render the adhesive quickly effective to secure it to the insole. 135
- 55 15. That improvement in methods of making shoes which consists in conforming the toe end of an upper heightwise of a last by the use of unheated wipers, and thereafter applying a heated presser to the marginal portion of the upper over an insole on the last around the toe end of the shoe bottom and forcing the presser inwardly in wiping engagement with the upper by use of the wipers. 140
- 60 16. That improvement in methods of making shoes which consists in conforming the toe end of an upper to the contour of a last and laying its marginal portion inwardly over an insole on the last by the use of wipers, retracting the wipers and applying a heated presser to the marginal portion of the upper to press it upon the insole, and then forcing the presser inwardly in wiping engagement with the upper by use of the wipers. 145
- 65 17. That improvement in methods of making shoes in which the marginal portion of the toe end of the upper is secured to an insole by an adhesive, which consists in laying the marginal portion of the toe end of the upper inwardly over an insole by the use of wipers, retracting the wipers and applying an adhesive to the margin of the upper, and thereafter applying a heated presser over the marginal portion of the upper and by use of the wipers forcing the presser inwardly over the shoe bottom in wiping engagement with the upper. 150

- ginal portion to render the adhesive quickly effective to secure it to the insole, and a support for said device mounted in determinate relation to said work support. 5
21. In a lasting machine, the combination with a shoe support, and means for laying the marginal portion of the upper of a shoe on said support inwardly over an insole, of a device for applying pressure and heat to the previously overlaid marginal portion of the upper while the shoe is on said support, and means mounted in determinate relation to said shoe support for controlling said device during both the overlaying and the pressure-applying operations. 10
22. In a lasting machine, the combination with a shoe support, and means for laying the marginal portion of the upper of a shoe on said support inwardly over an insole, of a treadle-operated member for pressing the previously overlaid marginal portion of the upper upon the insole while the shoe is on said support, and means for heating said member. 15
23. In a lasting machine, the combination with means for laying the marginal portion of an upper inwardly over an insole, of a heated pressing member arranged to press said overlaid marginal portion of the upper upon the insole, said member being movable in wiping engagement with the upper while pressing the upper upon the insole. 20
24. In a lasting machine, the combination with means for wiping the marginal portion of an upper inwardly over an insole, of a heated pressing member arranged to press the marginal portion of the upper upon the insole after it has been wiped inwardly by said means, said member being movable inwardly over the shoe bottom by the action of the wiping means thereon. 25
25. In a lasting machine, the combination with a work support, of wipers for conforming an end of an upper to the contour of a last on said support, a device for pressing the marginal portion of the upper around the end of the shoe bottom upon an insole on the last and for also heating said marginal portion while the last is on said support, and means mounted in determinate relation to said work support for controlling said device during both the upper-conforming and the pressing operations. 30
26. In a lasting machine, the combination with a work support, of wipers for wiping the marginal portion of an end of an upper inwardly over an insole on a last on said support, a heated presser movable to press the marginal portion of the end of the upper upon the insole after it has been wiped inwardly by the wipers and while the last is on said support, and a support for said presser mounted in determinate relation to said work support for movement to carry the presser toward operating position. 35
27. In a lasting machine, the combination with a work support, of unheated wipers for conforming an end of an upper to the contour of a last on said support, a heated presser for pressing the marginal portion of the upper upon an insole on the last around the end of the shoe bottom while the last is on said support, and means mounted in determinate relation to said work support for controlling said presser during both the upper-conforming and the pressing operations. 40
28. In a lasting machine, the combination with wipers for conforming an end of an upper to the contour of a last, of means for clamping the upper about the end of the last to hold it in conformity to the contour of the last, and a device 45
- for heating the marginal portion of the upper around the end of the shoe bottom and for pressing it upon an insole on the last while the upper is thus clamped. 50
29. In a lasting machine, the combination with a work support, of unheated wipers for wiping the toe end of an upper heightwise of a last on said support, and means for pressing the marginal portion of the upper upon an insole on the last around the toe end of the shoe bottom and for also heating said marginal portion while the last is on said support. 55
30. In a lasting machine, the combination with wipers for wiping the toe end of an upper heightwise of a last and for wiping the marginal portion of the upper inwardly over an insole on the last, of means for clamping the upper to the last around the toe exteriorly of the shoe bottom, and a device for applying pressure and heat to the inwardly extending marginal portion of the upper around the toe end of the shoe bottom while the upper is thus clamped. 60
31. In a lasting machine, the combination with wipers for wiping the marginal portion of the toe end of an upper inwardly over an insole, of means for clamping the upper about the toe, a member movable to press the marginal portion of the upper upon the insole around the toe end of the shoe bottom while the upper is thus clamped, and means for heating said member. 65
32. In a lasting machine, the combination with a shoe support, and means for laying the marginal portion of an end of the upper of a shoe on said support inwardly over an insole, of a heated presser curved similarly to the edge of the end of the shoe bottom and arranged to press the marginal portion of the upper upon the insole while the shoe is on said support, and a support for said presser mounted in determinate relation to said shoe support. 70
33. In a lasting machine, the combination with a shoe support, and wipers for wiping the marginal portion of an end of the upper of a shoe on said support inwardly over an insole, of a heated pressing member for pressing the marginal portion of the upper upon the insole around the end of the shoe bottom while the shoe is on said support, a movable support for said member mounted in determinate relation to said shoe support, and means for pressing said member upon the upper independently of the wipers. 75
34. In a lasting machine, the combination with wipers for wiping the marginal portion of an end of an upper inwardly over an insole, of a heated pressing member for pressing the marginal portion of the upper upon the insole, said member being movable inwardly over the shoe bottom by the action of the wipers thereon. 80
35. In a lasting machine, the combination with a shoe support, and means for laying the marginal portion of an end of the upper of a shoe on said support inwardly over an insole, of a heated pressing device mounted for movement into and out of position over the end of the shoe bottom while the shoe is on said support for pressing the marginal portion of the upper upon the insole around the end of the shoe bottom. 85
36. In a lasting machine, the combination with a shoe support, and means for laying the marginal portion of an end of the upper of a shoe on said support inwardly over an insole, of a heated pressing member for pressing the marginal portion of the upper upon the insole while the shoe is on said support, and a support for said member on which the member is movably mounted to tip 90

in different directions and thus to adjust itself to the contour of the shoe bottom.

37. In a lasting machine, the combination with a shoe support, and means for laying the marginal portion of the toe end of the upper of a shoe on said support inwardly over an insole, of a heated pressing member for pressing the marginal portion of the upper upon the insole while the shoe is on said support, a carrier movable to carry said member into or out of position over the toe end of the shoe bottom, a universal connection between said member and its carrier to permit the member to adjust itself to the contour of the shoe bottom, and means for operating the carrier to press the member upon the upper.

38. In a lasting machine, the combination with a shoe support, and means for laying the marginal portion of the toe end of the upper of a shoe on said support inwardly over an insole, of a heated pressing member mounted for movement into or out of position over the toe end of the shoe bottom while the shoe is on said support for pressing the marginal portion of the upper upon the insole, a handle to enable the operator to position the member in proper relation to the upper, and a treadle for operating the member to press it upon the upper.

39. In an upper-shaping machine, the combination with means for conforming an upper to the contour of a form and for shaping its marginal portion for attachment to a sole, of means for pressing on the upper to hold it in conformity to the contour of the form, and a device for applying pressure and heat to the marginal portion of the upper after it has been shaped by said first-mentioned means and while the upper is held by said pressing means.

40. In an upper-shaping machine, the combination with unheated means for conforming an upper to the contour of a form and for shaping its marginal portion over a sole, of a heated presser movable to press said marginal portion of the upper upon the sole while the form is in substantially the same position in the machine, and a support for said presser mounted for movement to carry the presser toward operating position.

41. In an upper-shaping machine, the combination with wipers for conforming an end portion of an upper to the contour of a form and for shaping the marginal portion of the upper, of means for holding the upper in conformity to the contour of the form, and a device for applying pressure and heat to the marginal portion of the upper previously shaped by the wipers while the upper is thus held.

42. In an upper-shaping machine, the combination with unheated wipers for wiping the toe end of an upper heightwise of a form, of means for clamping the upper about the toe to hold it in conformity to the contour of the form, and a device for applying pressure and heat to the marginal portion of the toe end of the upper while the upper is held by said clamping means.

43. In an upper-shaping machine, the combination with unheated means for wiping an upper heightwise of a form, of means for applying pressure and heat to the marginal portion of the upper along the same portion of the form as said wiping means while the form is in substantially the same position in the machine.

44. In a machine for lasting shoes in which the upper is secured to an insole by an adhesive, the combination with a work support, and means for conforming an upper to the contour of a last on said support and for laying its marginal por-

tion inwardly over an insole on the last, of a device for engaging the marginal portion of the upper and for pressing it upon the insole while the last is on said support, a movable support for said device mounted in determinate relation to said work support, and means for operating said device at the will of the operator to press it upon the upper and to maintain the pressure until the adhesive has hardened sufficiently to hold the upper in lasted position.

45. In a machine for lasting shoes in which the toes end of the upper is secured to an insole by an adhesive, the combination with a shoe support, and toe-embracing wipers for wiping the marginal portion of the toe end of the upper of a shoe on said support inwardly over an insole, of a presser mounted for movement into position to engage the marginal portion of the toe end of the upper while the shoe is on said support, and means for operating said presser at the will of the operator to press the upper upon the insole and to maintain the pressure until the adhesive has hardened sufficiently to hold the upper in lasted position.

46. In a machine for lasting shoes in which the toe end of the upper is secured to an insole by an adhesive, the combination with a shoe support, and toe-embracing wipers for wiping the marginal portion of the toe end of the upper of a shoe on said support inwardly over an insole, of a presser movable to engage the marginal portion of the toe end of the upper while the shoe is on said support after the wipers have been retracted from over the shoe bottom, a support for said presser mounted for movement to carry the presser into upper engaging position, and means for operating said presser to press the upper upon the insole and to maintain the pressure until the adhesive has hardened sufficiently to hold the upper in lasted position.

47. In a machine for lasting shoes in which the toe end of the upper is secured to an insole by an adhesive, the combination with a shoe support, and toe-embracing wipers for wiping the toe end of the upper of a shoe on said support heightwise of a last, of a presser for engaging the marginal portion of the toe end of the upper while the shoe is on said support and for pressing it upon an insole on the last until the adhesive has hardened sufficiently to hold the upper in lasted position.

48. In a lasting machine, the combination with a shoe support, and means for conforming the toe end of the upper of a shoe on said support to the contour of a last, of a device movable about an axis extending heightwise of the shoe into or out of position over the toe end of the shoe bottom, and means for operating said device to press the marginal portion of the upper around the toe end of the shoe bottom upon an insole on the last.

49. In a lasting machine, the combination with a shoe support, and means for laying the marginal portion of the toe end of the upper of a shoe on said support inwardly over an insole, of a member for pressing the marginal portion of the upper upon the insole around the toe end of the shoe bottom, a carrier mounted to swing about an axis extending heightwise of the shoe to carry said member into or out of position over the toe end of the shoe bottom, and a treadle for operating said carrier to press the member upon the upper.

50. In a lasting machine, the combination with a shoe support, and toe-embracing wipers for wiping the marginal portion of the toe end of the upper of a shoe on said support inwardly over

an insole, of a presser arranged to engage the marginal portion of the toe end of the upper wiped inwardly by said wipers, said presser being movable over the shoe bottom in wiping engagement with the upper, and means for operating the presser to press it upon the upper.

51. In a lasting machine, the combination with a shoe support, and toe-embracing wipers for wiping the marginal portion of the toe end of the upper of a shoe on said support inwardly over an insole, of a presser arranged to engage the marginal portion of the toe end of the upper, said presser being movable inwardly over the shoe bottom by the action of the wipers thereon.

15

52. In a lasting machine, the combination with a shoe support, and end-embracing wipers for wiping the marginal portion of an end of the upper of a shoe on said support inwardly over an insole, of a presser curved similarly to the edge of the end of the shoe bottom and constructed and arranged to engage the marginal portion of the upper initially at a distance from the edge of the upper after the wipers have operated thereon, said presser being movable from its initial upper-engaging position inwardly over the shoe bottom in wiping engagement with the upper.
